UNITED STATES PATENT OFFICE.

CHARLES A. ROWLEY, OF LOS ANGELES, CALIFORNIA.

CONTAINER FOR RADIocrystals AND WIRES USED FOR CAT WHISKERS.

Application filed November 28, 1925. Serial No. 72,040.

This invention relates to improvements in special packages.

An object of the invention is to provide a novel package of compact form which will 5 contain a crystal, such as is used in radio receiving sets, and a cat's whisker therefor.

Another object of the invention is to provide a package having a crystal and cat's whisker and to provide a transparent cover 10 for the package, enabling the contents to be readily inspected without requiring the removal of the crystal or cat's whisker or the opening of the package.

A further object of the invention is to provide a package containing a crystal and a cat's whisker, which is of rectangular form, so that a plurality of packages may be easily and conveniently packed for shipment or for storage.

20 With the foregoing and other objects in view which will be made manifest in the following detailed description and specifically pointed out in the appended claims, reference is had to the accompanying drawings for an illustrative embodiment of the invention, wherein:

Figure 1 is a perspective view illustrating the body or container part of the package and illustrating the contents as positioned 30 therein,

Fig. 2 is a vertical section through the container or body of the package,

Fig. 3 is a top plan view of the same,

Fig. 4 is a vertical section illustrating the 35 parts of the cover or closure in assembled relation, and

Fig. 5 is a top plan view of the package without the contents therein illustrating the package in its sealed form.

40 Referring to the accompanying drawings wherein similar reference characters designate similar parts throughout, the improved package consists of a container in the form of a block-like body 5, in the top of which there is formed a circular recess 7. The block-like body 5 is preferably rectangular in form and may be formed of wood or other material. A smaller recess or depression 6 is formed in the bottom of the recess 7 adjacent the center thereof. This depression is 45 adapted to receive a crystal mounting M, on which there is mounted a radio crystal C, as clearly shown in Fig. 1. The crystal mounting snugly fits within the depression 6 and projects upwardly into the recess 7, so that the top of the mounting is disposed adja-

cent the top of the block-like body 5. A strand of fine wire W, which constitutes a cat's whisker adapted to be used in connection with the crystal C, is coiled and is positioned within the recess 7 about the crystal mounting M. This strand of wire because of its resiliency tends to expand within the recess 7 and bears against the sides of the recess, so that it will frictionally maintain 65 itself within the recess about the crystal mounting.

On top of the block-like body 5 and over the recess 7 there is positioned a layer of transparent material 8, and over this there is positioned a square of paper 9, which is adhered to or otherwise fastened to the block-like body 5. The square of paper 9 has a large aperture formed therein of substantially the same size as the recess 7. It serves 70 to fasten the layer of transparent material 8 in place to permit the crystal and cat's whisker to be readily inspected through the transparent material. The square of paper 9 can be used as a label and may carry suitable directions or advertising matter. As the crystal mounting projects upwardly into the recess 7, its top is disposed slightly below the transparent layer 8, so that the transparent layer, while constituting a closure 75 for the recess 7, prevents the crystal mounting from falling out of the depression 6 in the event that the package is turned upside down.

From the above described construction it 80 will be appreciated that the improved package contains the essential elements of a radio detector, and furthermore the block-like body serves to effectively prevent these elements from becoming damaged. The form 95 of the body also permits a large number of packages to be conveniently packed for shipment or storage. A purchaser on wishing to withdraw the crystal and cat's whisker in opening the package breaks the layer of 100 transparent material 8 and then he can remove the crystal and cat's whisker.

It will be understood that various changes 105 may be made in the detail of construction without departing from the spirit or scope of the invention as defined by the appended claims.

I claim:

1. A package consisting of a container 110 in the form of a block-like body, in the top of which there is a circular recess, there being a depression formed in the bottom of the

recess, a crystal occupying said depression, a coiled strand of wire constituting the cat's whisker disposed within the recess and tending to expand because of its resiliency 5 against the sides of the recess, and a closure for the top of the recess, the crystal extending from the depression up through the recess a sufficient distance so that its top will be close enough to the closure whereby the 10 closure will keep the crystal from dropping out of the depression.

2. A package consisting of a container in the form of a block-like body, in the top of which there is a circular recess, said body 15 having such an external shape as to enable a plurality of the bodies to be easily packed together, there being a depression formed centrally of the bottom of the recess, a crystal occupying said depression, a coiled

strand of wire constituting the cat's whisker 20 disposed within the recess and tending to expand because of its resiliency against the sides of the recess, and a breakable closure formed of transparent sheet material secured to the block over the top of the recess. 25

3. A package consisting of a container in the form of a block-like body, in the top of which is formed a circular recess, there being a depression formed in the center of the bottom of the recess, a crystal mounting 30 fitting within the depression and extending upwardly into the recess, said crystal mounting having a crystal thereon, a strand of fine wire constituting a cat's whisker coiled about the crystal mounting within the recess, and means providing a transparent closure for 35 the top of the recess.

CHARLES A. ROWLEY.
